UNITED STATES PATENT OFFICE.

FRANCIS F. LONG, OF TYLER, TEXAS.

STIRRUP.

SPECIFICATION forming part of Letters Patent No. 565,478, dated August 11, 1896.

Application filed November 4, 1895. Serial No. 567,866. (No model.)

To all whom it may concern:

Be it known that I, FRANCIS F. LONG, a citizen of the United States, residing at Tyler, in the county of Smith and State of Texas, have 5 invented certain new and useful Improvements in Stirrups; and I do hereby declare the following to be a full, clear, and exact description of the invention, such as will enable others skilled in the art to which it applies to make and use the same.

My invention is a saddle-stirrup; and it consists in the novel construction and arrangement of its parts.

My invention is a stirrup constructed of 15 two side parts A, hinged together. The foot-piece B is mounted on springs, and the piece e, around which the stirrup-leather works, is also mounted on springs. The object of this construction is to give ease and grace to the 20 rider.

With this stirrup riding is easier both to man and beast than with stirrups without springs.

In the accompanying drawings, Figure 1 is 25 a side elevation of my invention, part in perspective and part in section. Fig. 2 is a perspective view of the foot-rest.

My invention is described as follows:

A are the side pieces.

30 a are the bottom pieces secured together by the hinge a'.

The side pieces have three cylindrical parts b, b', and b². The upper cylindrical parts b have, opening to the inner side of the stirrup, 35 slots c. The parts b also have, opening to the inner side of the stirrup, slots c', which are enlarged at c². The parts b² have slots c³, opening to the inner side of the stirrup, which enlarge at the points c⁴.

40 The upper end of one of the side pieces (which for the purpose of description I will call the "left-hand" side) is turned, forming a cross-bar d, recessed at d'. The right-hand piece is turned, forming a short bar d², which reaches to and fits in the recess d' of the bar d. To the lower face of the bar d is secured 45 a spring d⁴, having on its end a catch d⁵, which passes through a slot d⁶ in the upper end of the part A. The bar e, around which the saddle-strap f works, is provided with tenon ends e', which work up and down in the slot c. Between the bars d and e are secured

55 spiral springs e², the purpose of which is apparent. In the cylinders b' operate spiral springs g, the lower ends of which rest against the solid bottoms g', and in the cylinders b² operate spiral springs h. The springs are put in through the enlargements c² and c⁴.

The foot-piece B is provided with a flange i to strengthen it, and at each end with tenons j, side pieces k, provided with tenons l. The tenons l rest on the upper ends of the spiral springs g and work up and down in the slots c', while the tenons j rest on the upper ends of the spiral springs h and work up 65 and down in the slots c³. Between the bottom pieces a and the flange i are inserted spiral springs m.

The purpose of hinge a' is to allow the pieces A to be opened, so as to allow the 70 assembling of all the parts, and the spring d⁴ and catch d⁵ are to hold the pieces A together when so assembled.

The construction of this stirrup is so simple 75 that it may be put together without instructions. It is manufactured in regular sizes, so that when any one piece breaks or is lost it may be purchased and replaced.

Having described my invention, what I claim as new, and desire to secure by Letters 80 Patent, is—

1. A saddle-stirrup, consisting of the side pieces A, and bottom pieces a, hinged together at a', said side pieces being provided with cylindrical openings b, b' and b²; springs g and h, 85 working in the cylindrical openings b' and b²; foot-piece B, provided with tenons j, l, working on the upper ends of the springs g, h, and in the slots c', c³; cross-bar d, and d², to the upper ends of the side pieces a; spring-catch 90 d⁵, operating in slot d⁶; bar e, having tenons e', working up and down in slots c; spiral springs e², operating between bar e and spring d³, substantially as shown and described and for the purposes set forth. 95

2. In a saddle-stirrup, substantially as shown and described, the side pieces A, provided with a stirrup-strap piece, the lower ends of said side pieces A, provided with cylindrical openings b'; and slots c'; spiral springs g, operating in said cylindrical openings; foot-piece B, provided with side arms k, and tenons l, said tenons resting on the upper ends of springs g, and operating in slots 100

c', substantially as shown and described and for the purposes set forth.

3. In a saddle-stirrup, substantially as shown and described, the side pieces A, provided with a stirrup-strap piece, the lower ends of said side pieces provided with cylindrical openings *b*², and slots *c*³; spiral springs *h*, operating in said cylindrical openings; foot-piece B, provided with tenons *j*, said tenons resting on the upper ends of springs *h*, and operating in slots *c*³, substantially as shown and described and for the purposes set forth.

4. In a saddle-stirrup, substantially as shown and described, the side pieces A, provided with a stirrup-strap piece, the lower end of said side pieces provided with slots *c*³; foot-piece B, provided with tenons *j*, operat-

ing up and down in said slots; springs *m*, operating between the bottom pieces *a*, and the foot-piece B, substantially as shown and described and for the purposes set forth.

5. In a stirrup, substantially as shown and described, the cross-bars *d* and *d*², integral with the upper ends of the side pieces A, the cross-bar *e*, provided with tenons *e*', operating up and down in slots *c*, spiral springs *e*², secured between the cross-bars *d*, *d*² and *e*, substantially as shown and described and for the purposes set forth.

In testimony whereof I affix my signature in presence of two witnesses.

FRANCIS F. LONG.
